[57] CLAIM

The ornamental design for a child's riding vehicle, as shown and described.

DESCRIPTION

FIG. 1 is a side elevational view of a child's riding vehicle in accordance with our new design;

FIG. 2 is a top view thereof;

FIG. 3 is a front view thereof;

FIG. 4 is a rear view thereof; and

FIG. 5 is a bottom view thereof.

The dominant feature of the invention resides in the configuration and placement of the mud guards for the rear wheels, and the design of their attachment made to the body of the tricycle.

FIG. 1

FIG. 2

FIG. 3

FIG. 4

FIG. 5
